Filed May 10, 1967, Ser. No. 7,047

Term of patent 14 years

(Cl. D14—6)

FIG. 1.

FIG. 2.

FIGURE 2 is a side view as seen from the right of FIGURE 1, and portions are broken away to more clearly show the configuration of the instrument console; and

FIGURE 3 is a plan view as seen from the top of FIGURE 1, and portions are broken away to more clearly indicate the integration of the console to the generally vertical dash panel.

The dominant features of the design reside in the portions shown in full lines.

We claim:

The ornamental design for vehicle instrument console, as shown and described.
